CLAIM

The ornamental design for a lighting fixture as shown and described.

DESCRIPTION

FIG. 1 is a perspective view of a lighting fixture showing my new design.

FIG. 2 is a front elevation view of the lighting fixture of FIG. 1.

FIG. 3 is a right side elevation view of the lighting fixture of FIG. 1, the left side elevation view being a mirror image thereof; and,

FIG. 4 is a top plan view of the lighting fixture of FIG. 1. The broken lines depict portions of the lighting fixture that form no part of the claimed design. In FIGS. 1-4, the texture on the panel shades is fragmentarily shown for convenience of illustration, it being understood that the texture is continuous over the entire surface of the panel shades.
